C. KRANZ

SEPARABLE FASTENER

Filed Jan. 27, 1928

Fig. 2.

Inventor:
Clara Kranz.
by Charles O. Harvey
her Atty.

UNITED STATES PATENT OFFICE.

CLARA KRAZ, OF CHICAGO, ILLINOIS.

SEPARABLE FASTENER.

Application filed January 27, 1928. Serial No. 249,783.

This invention relates to separable fasteners and its principal object is to provide means for preventing the slider or sliding cam from accidentally slipping down along the jaws of the separable fasteners and permitting them to become unfastened. The invention has been designed especially for use in connection with separable fasteners of gaiters, and the like, where the tendency for the slider or sliding cam to slip or slide down along the jaws is particularly noticeable. However, its use is not limited to gaiters, and the like, but it may be used wherever found applicable.

Another object is to provide a simple, inexpensive and practical locking device capable of being applied to separable fasteners, now on the market, and with said objects and advantages in view this invention consists in a securing or retaining member arranged for engagement with the usual stringers upon which the jaws of separable fasteners are secured, whereby the slider is prevented from accidentally slipping down along the jaws. It further consists in the several novel features hereinafter fully set forth and claimed.

The invention is clearly illustrated in the accompanying drawing, in which:

Figure 1 is a perspective view of a separable fastener, embodying a simple form of the present invention;

Fig. 2 is a fragmental front elevation of the device;

Fig. 3 is a side elevation of the slider, the tab and the retaining device detached from the remainder of the separable fastener;

Fig. 4 is a plan of the parts seen in Fig. 2; and

Fig. 5 is a perspective view of the retaining member, looking at the rear side thereof.

Referring to said drawing, which illustrates a simple embodiment of the present invention, the reference character 6 designates a gaiter, overshoe, or the like, of conventional construction, provided with the usual co-acting locking jaws 7, of a well known separable fastener. As usual, the jaws are secured to stringers 8, ordinarily formed of woven tape secured to the opposite edges that define the opening at the instep. The jaws 7 are formed with the usual locking projections or lugs that enter

sockets or recesses in the contiguous jaws, 55 as is well understood.

A slider or sliding cam 9 of ordinary construction is slidably connected with the jaws as usual and has the customary Y-shaped channel for spreading the jaws apart when moved down along the jaws, and for bringing them together in locked condition when moved upward along the jaws. A tab or finger piece 10 is connected to the slider 9 by a loop 11, fastened to the slider and extending through a hole in the tab. The tab furnishes a convenient finger piece which is taken hold of in sliding the slider up or down along the jaws.

The parts thus far described comprise 70 a common and well known separable fastener. A particular objection to separable fasteners of this type is the tendency for the slider to slip down along the jaws permitting the jaws to unfasten above it. The ordinary bending action of the foot on the gaiter, especially has a tendency to cause the slider to slip down along the jaws, thereby releasing them and allowing the gaiter 75 to become opened.

To overcome this objectionable feature, I provide a securing device upon the tab or finger piece, which device engages with the stringers of the separable fastener in such manner that the slider is prevented from accidentally sliding down along the jaws. In the simple form of the invention shown, the tab is provided with a pair of wings 12 which project laterally from the side edges of the tab and are adapted to engage the stringers from behind. The wings are offset rearwards slightly, whereby the edges of the stringers may engage the transverse parts 13 of the offset wings. It is understood by those skilled in the art to which this invention pertains, that the edges of the stringers immediately above the Y-shaped slider diverge and the offset parts 13 of the wings engage in the crotch thus formed, and to all intents and purposes becomes wedged slightly therein, thereby supporting the slider by the loop 11 and effectively preventing it from slipping down along the jaws.

In use, the slider is drawn upwards by the tab to lock the jaws together, after which the wings are inserted behind the stringers as shown. To unlock the jaws, the wings of

the tab are disconnected from the stringers and the slider moved down by drawing the tab down as usual.

The offset wings are shown as formed upon a separate piece or strip 14, spot welded, brazed, soldered, riveted, or otherwise secured to the tab. This is merely one form of the construction contemplated, as the tab and wings may be made of one piece of metal, either cast or struck up with suitable dies. It may be made of suitable material other than metal, and may be given any suitable form or shape designed to effectively engage with the stringers or adjacent parts of the separable fastener for the purpose of retaining or securing it in place when raised to its locking position for the slider. The offset parts 13 of the wings may form a wedge-like member entering the crotch formed between the stringers above the slider and engaging with said edges.

More or less variation of the exact details of construction is possible without departing from the spirit of this invention; I desire, therefore, not to limit myself to the exact form of the construction shown and described, but intend, in the following claims to point out all of the invention disclosed herein.

30 I claim as new, and desire to secure by Letters Patent:

1. In a separable fastener having stringers, coacting locking jaws thereon, and a slider, slidably mounted on said jaws, a finger piece loosely connected to said slider and having a pair of laterally projecting

rearwardly offset wings adapted to engage the edges of the stringers and behind the edge portions.

2. In a separable fastener having stringers, coacting locking jaws thereon, and a slider, slidably mounted on said jaws, a tab, a loop on said slider and extending through a hole in the tab, and laterally projecting, offset wings on said tab adapted to engage behind said stringers.

3. A finger piece for sliders of separable fasteners, comprising a tab having a pair of offset laterally projecting wings adapted to engage behind the stringers of separable fasteners.

4. A finger piece for sliders of separable fasteners, comprising a tab connected to the slider, and formed with a pair of laterally extending, rearwardly offset wings adapted to engage behind the stringers of separable fasteners.

5. A finger piece for sliders of separable fasteners, comprising a tab loosely connected to the slider and formed with a pair of laterally extending, rearwardly offset wedge like wings adapted to engage the edge portions of the stringers of separable fasteners.

6. A finger piece for sliders of separable fasteners, comprising a tab loosely connected to the slider, and a pair of laterally extending rearwardly offset wings secured to said tab and adapted to engage behind the stringers of separable fasteners.

CLARA KRANZ.
